DESIGN FOR A DRESS

Doris Sennert, New York, N. Y.

Application September 2, 1938, Serial No. 79,700

Term of patent 3½ years

To all whom it may concern:

Be it known that I, Doris Sennert, a citizen of the United States of America, residing in New York city, in the Borough of Manhattan, county and State of New York, have invented a new, original, and ornamental Design for a Dress, of which the following is a specification, reference being had to the accompanying drawing, forming part thereof, wherein

Figure 1 is a front view of a dress showing my new design.

Figure 2 is a rear view of the dress shown in Figure 1.

The characteristic feature of my design resides in the combination on the dress disclosed of the specific waist section having contrastingly colored shirred areas arranged in the manner disclosed and the matching sectioned puffed sleeves as shown, in association with the blouse section having a stitched yoke and front panel closing as shown.

I claim:

The ornamental design for a dress, substantially as shown and described.

DORIS SENNERT.
